CLAIM

The ornamental design for a testing device, as shown and described.

DESCRIPTION

FIG. 1 is a front elevational view of the testing device;
FIG. 2 is a rear elevational view thereof;
FIG. 3 is a top plan view thereof;
FIG. 4 is a left-side elevational view thereof;
FIG. 5 is a right-side elevational view thereof;
FIG. 6 is a front, top, right perspective view thereof; and,
FIG. 7 is a back, top, left perspective view thereof.
The evenly spaced broken lines depict unclaimed parts of the testing device and form no part of the claimed design.
